UNITED STATES PATENT OFFICE.

WILLIAM W. DEAN, OF ELYRIA, OHIO, ASSIGNEE TO THE DEAN ELECTRIC COMPANY, OF ELYRIA, OHIO, A CORPORATION OF OHIO.

MEANS FOR PROTECTING OPERATORS' RINGING LEADS FROM SHORT CIRCUITS.

932,003.

Specification of Letters Patent. Patented Aug. 24, 1909.

Application filed August 8, 1905. Serial No. 273,455.

To all whom it may concern:

Be it known that I, WILLIAM W. DEAN, a citizen of the United States, residing at Elyria, in the county of Lorain and State of Ohio, have invented certain new and useful Improvements in Means for Protecting Operators' Ringing Leads from Short Circuits, of which the following is a specification, reference being had therein to the accompanying drawing.

My invention relates to telephone exchange systems, and particularly to the signaling apparatus and circuits employed therein.

It has for its object the provision of means for the protection of operators' ringing leads from short circuit.

Heretofore it has been customary to connect ordinary incandescent lamps in the ringing leads or branches from the power-board to the operators' keys. Some provision of this kind is necessary, for the reason that the resistance of lines varies widely, and if an operator should ring out over a line which was short-circuited or grounded, the lead would obviously also become short-circuited, but by including a sufficient resistance in the path of the ringing current any injurious rise thereof due to a short-circuit would be prevented.

The objections to the use of incandescent lamps in the manner stated are as follows: First, the voltage and effective output of the generators must be made very much higher than they would otherwise have to be, in order to overcome the resistance of the lamps when ringing; second, a lamp resistance acts in a manner directly the reverse of what is most desired, because its resistance falls when hot. Thus, when ringing over a long line, of high resistance the lamp resistance will be at its maximum, thereby cutting down the effective voltage thrown on the line; and when ringing over a short line, of low resistance, the lamp heats up and lowers its resistance, thereby raising the effective voltage on the line, and still further increasing the current.

My invention obviates the disadvantages of the lamp resistances, providing for a normal low resistance, rising to a maximum when the line resistance is below a definite predetermined quantity.

Briefly stated, it comprises a low resistance relay with a back contact armature, connected in series in the ringing branch or

lead. The relay is so adjusted that it will not pull up under normal ringing conditions, but when the operator rings on a short-circuited line the consequent large flow of current effectively energizes the relay, which pulls up its armature, thus breaking its own circuit to release the armature, and so on after the manner of a buzzer. The continued vibration of the armature introduces a very high resistance at the contacts, which to prevent burning I preferably make of carbon.

As a supplemental feature of the protective scheme, I provide means for indicating a short-circuit to the operator, so that it can be immediately reported to the wire-chief.

My invention is illustrated in the accompanying drawing, wherein the figure is a diagram showing a subscriber's line and sub-station apparatus, with a central office connecting circuit and ringing key.

In the drawing, A indicates the subscriber's station, provided with the usual transmitter, T, receiver, R, switchhook, H, and ringer, Q. The line wires 1 and 2 terminate at the central office at the springs j and j' of the line jack J, which may also have a test thimble j''. When in a condition of disuse, the jack springs are closed upon the contact anvils forming terminals of the circuit of the line annunciator, L. For simplicity of illustration I have shown an annunciator of the magneto drop shutter type, but it is to be understood that my invention is applicable to any type of system, and that its essential features are unchanged in any case, whether the switchboard be a transfer or a multiple board, and its circuits supplied with current from a central office battery for all purposes or from local batteries and magneto generators for talking and signaling respectively.

For interconnecting the lines at the central office cord circuits are provided, each with terminal plugs P and P', having the tip and sleeve contacts connected together respectively by the conductors 3—5 and 4—6. For a magneto system such as the diagram indicates, a clearing-out annunciator is bridged across the cord at L'. A suitable listening key is connected in each cord, but this is omitted from the illustration.

The operator's ringing key is shown at K. This has the usual or any desired form of button or lever manipulated by the operator

to move the contact springs k and k' , which normally rest on contact points forming the terminals of the cord conductors 5 and 6 whereby the tips p and p' and the sleeves p' 5 and p^2 are joined. When the springs k and k' are separated they leave the normal or cord terminals and make contact with the terminals of the generator circuit or ringing lead 7-8, thus connecting the generator G 10 through conductors 3 and 4 to the plug P and so to the line 1-2, assuming the plug to have been inserted in the jack J.

The system thus far described is old and well known, and as I have stated may be 15 varied in many ways without affecting the essential features of my invention. According to present practice, an incandescent lamp would be interposed in the path 7 between the generator bus 14 and the key K. I have 20 discarded the lamp, however, and in its place I introduce the relay M, whose windings are connected on one side to the wire 7 and on the other through wire 9 with its own armature m , or a contact moved thereby. 25 The armature normally rests against a back contact m^2 , and the actual contact faces or points I make rather heavy and of carbon, to enable them to pass a heavy current and stand sparking without injury. From the 30 contact m^2 the wire 14 passes to the generator G, this and the wire 12 in the drawing indicating the buses. The wire 12 has the ground tap 10.

For the purpose of indicating a short-circuited or grounded line when ringing, I connect a high resistance relay N in a shunt around the contacts m^2 , its circuit being from wire 14 through wire 13 and by wire 11 to the armature m . The armature n of 35 this relay controls the continuity of a local circuit 15-16, containing a signal lamp O and a suitable source of current, and is normally retracted by the spring n' .

The relay M is so designed that a large 40 current is required to operate it, this being accomplished in a manner well known to all engineers, by suitably arranging its magnetic circuit and adjusting the retractile spring m' . Upon a predetermined rise in 45 current, however, it will operate by vibrating its armature as a buzzer, opening and closing the contacts at m^2 with great rapidity. Such rapid opening and closing introduces a very high resistance at the contacts, 50 which may be regulated by adjusting the amplitude and rate of the vibrations. By suitably proportioning the turns of wire in the winding, the mass and relative effects of the parts of the magnetic circuit, and the 55 strength of the spring m' , I may produce a resistance inversely proportional to the current or to that of the line over which the current passes, the lines being thus ballasted during ringing. It will be observed that 60 the operation of this regulating relay M is

entirely automatic, and that the operator without special means for noting its action would not be aware of any change in condition during ringing. With the relay N, however, and its lamp O, the operator can 70 note and report the vibration of the regulator. When the armature m commences to oscillate and thereby introduces additional resistance in the branch circuit 14- m^2 - m , current is diverted through the relay N to 75 operate the latter. The armature n being attracted, the circuit 15-16 is closed, and the lamp O lights. The lamp may be placed in any convenient part of the switchboard, 80 may be designated as the "ringing lamp," and remain unobserved except in cases of line trouble, when it will light up, and the operator being thereby notified may report the same. The rise of current in the line thus strengthens the flux in the relay M, 85 which by vibrating the armature m raises the resistance in the shunt around relay N, causing a rise in current therein which eventually overcomes the spring n' and lights the ringing lamp O. The operation 90 is symmetrical and properly directed to produce symmetrical ringing effects. I believe that I am the first to succeed in attaining this desirable object, and I shall accordingly claim the same broadly. 95

I do not desire to limit myself to the use of the indicating relay or signal with the regulating relay or resistance, as the latter may obviously be employed alone with advantage. 100

Many variations may be made in the arrangement and manner of use of the invention, and all such are contemplated by me.

It will be observed in the beginning of this specification that I have referred to the 105 inclusion of lamp resistances in operators' ringing leads. I have also pointed out the objections to this arrangement, one of which is that the lamp resistance varies inversely as the current. The distinctive feature of 110 my present invention is that it covers a compensating resistance, the lamps heretofore employed being merely limiting resistances, with their only variation in a reverse direction to that which would tend to compensate for variation in the line resistance. I shall employ the word "compensating" 115 hereafter in my claims, in order to mark this distinctive feature of difference. I may here define the term compensating resistance 120 as one which varies inversely as that with which it is to be used, so as to partially or wholly equalize the total resistance in the ringing circuit for lines of different lengths.

Having described my invention, what I 125 claim, and desire to secure by Letters Patent of the United States, is:

1. In a telephone system, a line circuit, a source of current supply therefor a connection from such source to the line a compen- 130

- sating resistance interposed in such connection, and electromagnetic means in such connection for varying such resistance.
2. In a telephone system, a line circuit, 5 a source of current supply therefor, a connection from such source to the line, a compensating resistance interposed in such connection, and electromagnetic means in such connection for increasing such resistance as 10 the current delivered from such source to the line increases.
3. In a telephone exchange system, a plurality of line circuits, and central office connective circuits for inter-connecting the 15 lines, a source of calling current at the central office, means to connect the same with a connective circuit, and a magnetically controlled variable resistance in said connection, together with an indicating device 20 adapted to indicate the condition of the resistance device.
4. In a telephone system, a line circuit, a source of ringing current, a switch for connecting said source to the line, and a relay 25 having its circuit completed and its operation continuously controlled through a back contact of its own armature, interposed in the circuit between the source and the switch.
5. In a telephone system, an operator's 30 connective cord circuit, comprising connecting cords with terminal plugs, a ringing key connected to the same, and connections from said ringing key to a suitable source of ringing current; together with a buzzer connected in the lead between the source and the ringing key.
6. As a means for protecting telephone operators' ringing leads, a variable resistance device connected therein and comprising 40 a buzzer relay having carbon contacts.
7. As a means for protecting telephone operators' ringing leads, a variable resistance device connected therein and comprising a buzzer relay having carbon contacts 45 in series with the winding of its magnet.
8. In a telephone exchange system, an operator's cord circuit and ringing key, and connections therefrom to a ringing generator, a buzzer relay connected between the generator and the ringing key to serve as a variable resistance, and an indicating device 50 controlled by said relay.
9. In a telephone exchange system, an operator's cord circuit and ringing key, and connections therefrom to a ringing generator, a buzzer relay connected between the generator and the ringing key to serve as a variable resistance, and an indicating device 55 connected so as to be actuated when the buzzer relay operates.
10. In a telephone exchange system, an operator's cord circuit and ringing key, and connections therefrom to a ringing generator, a buzzer relay connected between the generator and the ringing key to serve as a variable resistance, and an indicating device 60 connected in a shunt around the contacts of the buzzer.
11. In a telephone exchange system, an operator's cord circuit and ringing key, a generator of ringing current, suitable connections from said source to said ringing key, and a buzzer relay included in said connections, the windings of said relay being 65 of relatively low resistance.
12. In a telephone system, a connective circuit and a ringing key or switch therefor, a ringing generator and connections therefrom to the switch, a variable resistance 70 normally at a minimum value included in said connections, and an indicating device 75 in a shunt around said resistance.
13. In a telephone system, a connective circuit and a ringing key or switch therefor, a ringing generator and connections therefrom to the switch, a variable resistance normally at a minimum value included 80 in said connections, and an indicating device 85 in a shunt around said variable resistance device.
14. In a telephone system, a ringing key or switch, a ringing generator, and ringing leads extending from said generator to said switch, a low-wound buzzer relay with carbon contacts connected in one of said ringing leads, a relatively high-wound magnet connected around the contacts of said buzzer relay, and a signal controlled by said high-wound magnet.
- In testimony whereof I affix my signature in presence of two witnesses.
